UNITED STATES PATENT OFFICE

EUGENE L. SCHELLENS, OF POINTE CLAIRE, QUEBEC, CANADA, AND JOEL S. COFFIN, JR., OF LISBON, NEW HAMPSHIRE, ASSIGNEES, BY MESNE ASSIGNMENTS, TO C-S ENGINEERING COMPANY, A CORPORATION OF DELAWARE

LOCOMOTIVE FRONT END

Application filed August 1, 1923. Serial No. 654,975.

This invention relates to locomotives and front end improvements thereof.

One of the primary objects of our invention is to draft the locomotive with minimum back pressure in the cylinders whereby the concomitant disadvantages incident to the standard practice of drafting locomotives in which back pressures run quite high, are overcome.

10 Another object of the invention is to obtain increased flexibility of the locomotive boiler whereby high boiler overload, as well as normal boiler load conditions, can be obtained with minimum back pressure.

15 Still another object of the invention has to do with improvements in the design, construction and disposition of front end exhauster devices, the advantages of which will be hereinafter more fully pointed out.

20 A further object of the invention has to do with the effective reclamation and utilization of the heat of the exhaust steam and of the waste gases for heating feed water.

The foregoing, together with such other 25 objects as may hereinafter appear, or are incident to our invention, we obtain by means of a method and construction illustrated in the accompanying drawings in preferred form, wherein:

20 Fig. 1 is a transverse section through a locomotive front end, illustrating one form of our improvements; Fig. 2 is a side elevation of Fig. 1; Fig. 3 is a section taken on the line 3—3 of Fig. 1; Fig. 4 is a plan view of the

35 exhauster device of Fig. 1; and Fig. 5 is a section corresponding to Fig. 1 but illustrating still another form of the invention.

Referring now to Figs. 1 to 4, inclusive, the 40 reference character A indicates the smoke box located in advance of the flue sheet of the boiler B. The usual stand pipe is omitted and in place thereof we prefer to substitute a multiple jet nozzle 7, the jets 8 of which and the exhaust passages 9 in the cylinder saddle casting are so designed that the exhaust steam from the cylinders is discharged at a minimum high limit of back pressure, say for example, in the neighborhood of 6 lbs., which is much lower than the maximum back pressure produced in standard practice. With a

maximum back pressure of say 6 lbs., the exhaust steam will be discharged at relatively low velocity and pressure and the draft produced thereby, while sufficient to enable the locomotive to be run to a terminal, would be normally insufficient to fire the locomotive at the higher rates demanded under average conditions of operation. The advantages of reduction of back pressure in so far as the engines of the locomotive are concerned, will 60 be readily understood.

To supplement the exhaust steam, we provide an exhauster device such as the turbo exhauster C. This exhauster can be normally continuously operated at speeds sufficient to produce the additional draft required to fire the locomotive at the rate demanded by the particular operating conditions. By using exhaust steam at relatively low pressure and low velocity for creating a part of the draft required, the pulsations will not be as marked as in a locomotive drafted in accordance with standard practice, and this, together with the continuous draft effect of the turbo exhauster, enables us to adequately draft the locomotive 75 with a draft which, in comparison, is of lower velocity and of more continuous and uniform character, among the more marked additional advantages of which are the reduction in stack losses of unconsumed combustibles, the prevention of "pulling holes" in the fire bed, and the obtaining of more uniform draft conditions in the flues and in the fire box and, therefore, in the fire.

The utilization of exhaust steam at relatively low pressure and low velocity, supplemented by the exhauster, secures a very high degree of boiler flexibility, with minimum exhauster fan speeds under normal conditions, the fan, however, having capacity such as to produce high boiler overload at desired periods, such for example, as when the locomotive is equipped with a booster for use in aiding the main drivers in starting the train and in maintaining it in motion at low speeds on heavy grades under which condition extremely high rating may be frequently called for during short intervals.

In carrying out our invention, we locate the turbo exhauster mechanism C at the 100

upper end of the stack D (which in this instance is also shown as being a feed water heater arrangement), the exhauster mechanism consisting of the fan 10 preferably having peripheral turbine buckets and the peripheral turbine motor means 11, operated by steam, preferably exhaust steam, as will further appear. The fan is mounted on a vertical shaft 12 which in turn is supported by means of the bearing 13 and the thrust bearing 14 in a housing 15 on the hub portion 16 of the spider 17, which is carried in the top of the stack. The spider 17 also carries the outer ring of the turbine, so that the spider, turbine and fan mechanism can be removed and installed as a unit. The housing 15, the bearings and the shaft, are further enclosed by a casing 18 which serves as an oil well so that the shaft revolves in oil.

We are aware that exhauster fans have been used for drafting purposes but heretofore, in so far as we are aware, all of the arrangements have been objectionable because of the location and disposition of the parts, in which connection one of the most serious problems to be encountered is the proper lubrication of the rotating parts and their protection from the products of combustion and the heat thereof. It will be seen that by our arrangement the exhauster parts are most favorably disposed with respect to the dirt and the heat of the products of combustion and the shaft and bearings thoroughly lubricated by an arrangement which additionally serves to obviate heating difficulties. With the bearings immersed in oil contained in the relatively large casing 18, it will be seen that the turbo exhauster should require little, if any, attention between shoppings. In addition, the fan being of large diameter, can very easily develop the necessary horse power at comparatively low angular speeds and at high bucket velocity, insuring maximum efficiency and adaptability for heavy duty. The spokes of the spider direct the gas flow upwardly so as to allow the gas to be picked up by the rotating blades of the fan, which makes for higher efficiency.

The advantages of this arrangement and disposition of the exhauster mechanism are further increased when, as shown, the stack is utilized as a means for heating feed water. In this connection it will be observed that the stack B consists of a practically closed casing 19—of which the casing 18 forms a part—through which casing extend a plurality of tubes 20, the number of which corresponds with the number of jets 8, such tubes increasing in area upwardly and having their upper ends discharging opposite the blades of the fan. The connections 21 lead from the injectors or feed pump or the like and introduce feed water into the casing 19 in the center thereof. At the upper part of

the casing is an outlet 22 provided with a valve 23, and at the bottom is a cleanout pipe 24.

By splitting up the exhaust steam into a plurality of small jets, the surface or entrainment area is greatly increased so that maximum entrainment of the gases of combustion is obtained, with consequent increase in efficiency of the exhaust steam as a producer of draft.

By this arrangement a portion of the heat of the exhaust steam and also a portion of the heat of the waste gas is reclaimed and utilized for heating the feed water, in which connection the rate of heat transfer is quite rapid, as for a given area of heat-absorbing surface, the rate of heat transfer is a function of the rate of flow through the tubes and as these are comparatively long and the flow of exhaust steam and gaseous products relatively fast, the feed water heater is very efficient.

It will be noted that the feed water arrangement, considered as a whole, extends well down into the front end and close to the jets 8. This arrangement, when considered in connection with the multiple jet nozzle, is not objectionable but, on the contrary, will produce more uniform pull on the flues than in standard practice. The use of a spark arrester may also be dispensed with because of the lower velocity of the exhaust steam and waste gases and the cooling effect of the feed water heater. Difficulties with respect to condensation are also avoided because of the mingling of the waste gases with the steam and because of the turbo exhauster. With the feed water heater casing closed at top and bottom, centrally of the ring of tubes, there is no opportunity for back draft down the center which would overcome the increased advantages of the larger entraining surfaces secured by splitting up the exhaust steam. The use of a single combining tube 20 for each jet secures a maximum efficiency.

With regard to the proportioning of the capacities of the fan and the ejector, the ejector mechanism, as previously pointed out, should have capacity to produce sufficient steam to enable the locomotive to make its way to a terminal, and the fan should have sufficient capacity to produce high boiler overload and yet supplement the ejector properly for average conditions at relatively low fan speeds.

With regard to back pressure, assuming the device is to be applied to a locomotive which, in standard practice, would be drafted by a $5\frac{1}{2}$ " nozzle, we would prefer to substitute eight $2\frac{3}{4}$ " nozzle jets with a total area of approximately 47 sq. in. as compared to about $23\frac{1}{2}$ sq. in. In other words, the area would be a little over twice as great and the entrainment surface would be over two and one-half times as great. The jet velocity of the multi-

ple arrangement would be about one-half that of the single tip nozzle with the result that the ejector mechanism would have a capacity of from half to three-quarters of the 5 single tip, the fan making up the balance.

When the turbo exhauster fan is operated by exhaust steam, as shown, we prefer to provide a receiver 25 in parallel with the jets, to which end the supply of steam for the receiver 10 is taken off from one of the exhaust passages 9 at a point closely adjacent a valve chest 26, as indicated. The purpose of the receiver is to provide sufficient volume of steam to secure a substantially uniform operation of the 15 fan, or stated in other words, the receiver serves to obliterate the impulses of the exhaust steam from the respective cylinders, in so far as the steam supply for operating the fan is concerned. Incidentally, the use of 20 a receiver has the same effect on the jets 8, for during the intervals between impulses exhaust steam will work both ways from the receiver, namely, to the fan and to the jets. Thus the receiver, the low back pressure jets, 25 and the fan all cooperate to produce the lower velocity, the lower pressure but substantially uniform and continuous draft hereinbefore referred to.

A valve 27, suitably operated from the cab, 30 controls the amount of steam passing from the receiver to the turbo exhauster for regulating the speeds thereof.

With regard to the fan, it will be noted that the heat absorbed by the blades is dissipated in revolution by contact with the air before this heat can reach the bearings, and the cooling effect of the blades is also carried over into the spokes of the spider.

In the arrangement shown in Fig. 5, the 40 exhaust steam and the waste gases are passed separately through the feed water heater, the heater consisting of an outside shell 30, an inside shell 31 and the top and bottom closure plates 32 and 33. The inner shell 31 is connected with the exhaust steam header 34 by means of an accordion member 35 to take care of expansion and contraction and has its ends closed by two tube sheets 36. A nest of tubes 37 is arranged within the inner shell 31, the 45 exhaust steam passing through such tubes and out to the atmosphere through the space 38 around the fan shaft housing. The size and number of the tubes 37 and the area of the opening 38 determines the back pressure of 50 the exhaust steam.

The waste gases pass through the tubes 39 under the influence of the fan and the exhaust steam. The shell 31, near its lower portion is provided with a plurality of openings 40 so 55 that the feed water, which is introduced into the upper portion of the inner shell through the pipe or pipes 41 circulates downwardly and outwardly into the space between the two shells and from thence, when the ejectors are 60 in operation, flows out of the upper portion

of the chamber defined by the two shells, as before. Thus, the water is subjected to separate distinct heating stages before leaving the heater, which gives a higher rate of heat transfer and increased efficiency, and by virtue of the absorption of heat from the products of combustion, the latter are cooled and become more dense. Therefore, the exhauster is not only effectively protected against overheating but its capacity is increased because it acts upon a more dense gas. 70

It will, of course, be understood that the turbo-exhauster may be utilized simply as a governor. 75

What we claim is:

1. In a locomotive draft appliance, a stack, a fan, a turbine for driving the fan, and a manifold for supplying an operating fluid disposed annularly of the stack. 80

2. In a locomotive, a stack, a draft creating fan at the outlet thereof, and peripheral turbine driving means for the fan disposed annularly around said stack. 85

3. In a locomotive, a stack, a fan therefor rotating about a substantially vertical axis, and a turbine driving means therefor arranged peripherally of the stack. 90

4. In a locomotive, a stack, a fan therefor rotating about a substantially vertical axis, and a turbine driving means therefor arranged peripherally of the stack and fan. 95

5. In a locomotive, a stack, a fan therefor at the outlet thereof rotating about a substantially vertical axis, a shaft located substantially centrally of the stack, bearing means for the shaft supported from the stack, and a casing enclosing the bearing means. 100

6. In a locomotive, a stack, a spider having a central hub, a fan having a substantially vertical shaft carried by said hub, and a casing cooperating with the hub to enclose the shaft. 105

7. In a locomotive, a stack, a spider having a central hub, a fan having a substantially vertical shaft carried by said hub, and a casing cooperating with the hub to enclose the shaft, together with a turbine driving means for the fan arranged peripherally of the fan and stack. 110

8. In a locomotive, a stack, a fan, a support therefor, and a turbine driving means for the fan; the fan, support and driving means being supported by, and removable as a unit from, the stack. 115

9. The combination in a locomotive, of an exhaust fan, and an economizer in advance of the fan including a plurality of tubes thru which products of combustion pass to the fan and by which feed water is heated and the temperature of the gases lowered. 120

10. In a locomotive, a stack, an exhaust nozzle adapted to discharge the exhaust steam at a velocity such as to but partially draft the locomotive, and means for supplementing the exhaust steam to draft the locomotive, said 130

- means comprising an exhauster fan mounted on a vertical axis in the upper part of the stack.
11. In a locomotive, a multi-tube stack, and a multi-jet exhaust steam nozzle together with an exhauster means at the upper end of the stack.
12. In a locomotive, a multi-tube stack, and a multi-jet exhaust steam nozzle, together with an exhauster fan at the upper end of the stack.
13. In a locomotive, a stack feed water heater casing, a plurality of tubes extending therethrough, and a multi-jet exhaust steam nozzle, together with an exhauster means supplementing the exhaust steam.
14. In a locomotive, a multi-jet nozzle, and a stack comprising a ring of tubes with means preventing down draft around the tubes.
15. In a locomotive, a unitary stack, a multiple jet nozzle, and a combining tube for each jet in said stack such tubes increasing in area upwardly together with supplemental drafting means at the upper end of said tubes.
16. In a locomotive, a stack, a multiple jet nozzle, a combining tube for each jet extending up through the stack, and an exhauster fan above said tubes.
17. In a locomotive, a stack, a multiple jet nozzle, combining tubes for the jets located in the stack and increasing in cross-sectional area upwardly, and an exhauster fan above said tubes.
18. In a locomotive, exhaust steam draft creating means, a receiver in parallel therewith, a turbo exhauster, and a connection for supplying steam from the receiver to the turbo exhauster, together with means controlling the steam supplied to the turbo exhauster.
19. In a locomotive, exhaust steam draft creating means, a receiver in parallel therewith, a turbo exhauster, and a connection for supplying steam from the receiver to the turbo exhauster, said means being constructed to produce a back pressure insufficient to fully draft the locomotive but sufficient to ensure adequate steam supply for the turbo-exhauster.
20. In a locomotive, an exhaust steam actuated turbo exhauster, and means for supplying exhaust steam thereto substantially uniformly.
21. The method of drafting a locomotive which consists in splitting up part of the exhaust steam into a plurality of low pressure, low velocity jets, in utilizing said jets to effect a partial drafting of the locomotive, and in meeting additional draft requirements by utilizing another part of the exhaust steam to create a substantially non-pulsating draft.
22. In a locomotive, a stack feed water heater casing, a plurality of tubes extend-
- ing therethrough, and a multi-jet exhaust steam nozzle, together with an exhauster fan, the bearing means of which is surrounded by feed water.
23. In a locomotive, a stack feed water heater, and an exhauster fan having bearing means, said means being immersed in the feed water.
24. In a locomotive, a stack feed water heater, and an exhauster fan having bearing means, including an oil containing casing immersed in the feed water.
25. In a locomotive front end construction, a smoke-box, a stack, a draft fan at the top of the stack, a plurality of exhaust nozzles in the smoke-box, a plurality of combining tubes in said stack, each of which is in alignment with a nozzle, said tubes delivering to the fan, bearing means in the stack for the fan, and means for circulating feed-water in proximity to said tubes and bearing means adapted to cool the products of combustion indirectly and the bearing means directly.
26. In a locomotive front end construction, a smoke-box, a stack, a draft fan at the top of the stack, a plurality of exhaust nozzles in the smoke-box, a plurality of combining tubes in said stack, each of which is in alignment with a nozzle, said tubes delivering to the fan, bearing means in the stack for the fan, and means for circulating feed-water in proximity to said tubes and bearing means adapted to cool the products of combustion indirectly and the bearing means directly, together with turbine driving means actuating said fan.
- In testimony whereof, we have hereunto signed our names.
- E. L. SCHELLENS.
